UNITED STATES PATENT OFFICE

TRAYHARN DAVIS, OF BERKELEY, CALIFORNIA

DISAPPEARING ROTARY HYDROCARBON FUEL BURNER

Application filed March 14, 1928. Serial No. 261,597.

This invention relates generally to hydro-carbon fuel burners; it has especial relation to such burners of the rotary type wherein the rotary element operates within the heat zone of the completed structure; and it consists in the novel construction, arrangement and combination of parts, hereinafter described and later claimed.

The object of my invention is to provide a device of this character wherein it is possible, by a simple, convenient, and efficient mechanical arrangement of parts, to raise or to lower the burner into or out of operative position.

When in operative position the rotary element, or cup, of the burner, by means of which the fuel is atomized and fed into the fire-box, travels at great velocity (often approximating 4,000 R. P. M.), and, therefore, it must at all times be positively centered to be effective. In the operation of devices of this character, prior to my discovery, it has been the practice to cause the cup to be revolved and the air current to be maintained for a considerable period of time after the fuel supply for the burner has been shut off, otherwise the intense heat (often as high as 1,500° F.) radiated from the firebox tends not only to cause the unconsumed fuel left in the cup to cake, or to carbonize, on the cup, but, also, tends to warp the cup and shaft supporting the cup, thereby destroying the efficiency of the entire structure.

In my structure I provide mechanism for lowering and raising the burner. I now make it possible to withdraw the cup from the influence of the intense heat of the fire-box, thereby eliminating all danger to the cup and its shaft from the effects of radiated heat. In my device, also, the prime mover for the cup may be shut off simultaneously with the shutting off of the fuel supply and air current with no ill effects, for when the burner is in a lowered, or inoperative, position, outside air currents rush in through the opening in the fire-box formerly filled by the burner and out through the furnace stack of the complete structure. Such air currents are sufficient to cool the structure, carry upward all heat waves (the results of radia-

tion); and effectually prevent any caking or carbonizing of fuel on the cup, and prevent any warping of parts.

In order that my invention may be clearly understood and readily carried into effect, the same is hereinafter described with reference to the accompanying drawings, in which similar numerals indicate like parts. Of such drawings,

Fig. 1 is a side elevation of my device, showing the burner in operative position;

Fig. 2 is a view similar to Fig. 1, showing the burner lowered, or out of operative position;

Fig. 3 is a plan view, partly broken, the parts in the same position as in Fig. 2;

Fig. 4 is a front elevation, the parts in the same position as in Fig. 2.

In detail, my construction is as follows: Rising from a base, 2, are vertical supports, 3, which support a guide-ring, 4, adapted to receive the burner when the same is in operative position. The burner, as shown in the drawings, is of the rotary type. It comprises, generally, a vertically disposed cylindrical body, A, an open head, B, a closed base, C, and a rotatably fuel cup, D. For a more detailed description of the specific burner preferred by me, reference is hereby made to my co-pending application for patent on a liquid fuel burner, filed May 24, 1927, Serial No. 193,763.

An inwardly extending flange, 5, on said ring, 4, cooperates with an outwardly extending flange, 6, on said head, B, and by reason of the co-operation of these two flanges the upward movement of the burner is limited.

The burner is so constructed that it may be either raised or lowered. Integral with the cylindrical body, A, are lugs, 7, adapted to receive vertical guides, 8, attached to and rising from the base, 2. Interposed between said lugs and said base are powerful compression springs, 9, which exert a constant upward pressure against said cylindrical body, A, and tend to keep it in its operative position, as shown in Fig. 1. Pivoted to said base, as at 10, is a hand lever, 11. A bell-crank, 12, mounted on said base, as at 13, is

55

65

75

95

100

connected with the lever, 11, by means of a connecting rod, 14, pivoted at one end to said lever, as at 15, and at the other end to the backward arm of said bell-crank, as at 16. The forward end of said bell-crank is slotted, as at 17, to engage a pin (not shown) mounted on the under side of said closed base, C.

Said lever, 11, is provided with a spring controlled pawl, 18, adapted to engage notches, 19, provided in the vertical segment ratchet-bar, 20, rising from said base. When the pawl is in the backward notch, as shown in Fig. 1, the burner is in its normal, or operative, position; when the pawl is in the forward notch, as shown in Fig. 2, the burner is in its lowered, or inoperative, position. When the burner is in a lowered, or inoperative, position, so long as there is any stack draft, due to heated conditions of the firebox, currents of air from without, as indicated by arrows in Fig. 2, will sweep over the top surface of the burner, the rotatable cup and shaft, into the opening in the ring, 4, caused by the withdrawal of the burner head, and out the stack,—thereby carrying all heat waves upward and away from the burner, rotatable fuel cup, and shaft.

I would have it understood that the construction herein illustrated and particularly described is intended to exemplify what is at present regarded to be the preferred embodiment of my invention, and that the invention may be otherwise and variously embodied without departing from its spirit or the scope of the subjoined claims.

Having thus described my invention, what I desire to claim and to secure by Letters Patent is:—

1. In a hydrocarbon fuel burner of the rotary type, a burner susceptible of fixed adjustments up and down, a pressure member for holding said burner in operative position, guides for said burner, and means for changing said burner to an inoperative position and for retaining the same in a fixed inoperative position against the action of said pressure member for cooling purposes.

2. In a hydrocarbon fuel burner of the rotary type, a burner susceptible of fixed adjustments, up and down, a pressure member for holding said burner in operative position, guides for said burner, and means for withdrawing said burner from operative position after use to an inoperative position against the action of said pressure member and for holding the same in said inoperative position without the heat zone during the cooling process.

3. In a device of the character described, a frame, a movable rotary burner, a pair of flanges co-operating to limit the movement of the burner in one direction, a pressure member for holding said burner in operative position, and means for moving the burner

into or out of operative position, and means for holding said burner in locked inoperative position against the action of said pressure member for cooling purposes.

4. In a device of the character described, a frame, a vertically disposed rotary burner, a pressure member for holding said burner in operative position, guides for said burner, a guide-ring provided with an inwardly extending flange constituting a stop for the upward movement of said burner, and means for moving said burner into or out of operative position, and means for retaining said burner in fixed inoperative position against the action of said pressure member without the heat zone for cooling purposes.

5. In a device of the character described, a rotatable burner susceptible of up and down fixed adjustments, a pressure member for holding said burner in operative position, guides for said burner, a stop to limit the movement of said burner in one direction, and means for moving said burner into or out of operative position, and means for holding said burner in locked inoperative position against the action of said pressure member for cooling purposes.

In testimony whereof, I have hereunto set my signature.
